UNITED STATES PATENT OFFICE.

FRED H. VAN LOOZEN, OF CLEVELAND, OHIO, ASSIGNOR TO THE VAN LOOZEN AUTOMATIC PRINTING PRESS COMPANY, OF CLEVELAND, OHIO, A CORPORATION OF OHIO.

PRINTING-PRESS.

No. 928,525.

Specification of Letters Patent. Patented July 20, 1909.

Application filed May 4, 1908. Serial No. 430,796.

To all whom it may concern:

Be it known that I, FRED H. VAN LOOZEN, a citizen of the United States, residing at Cleveland, in the county of Cuyahoga and State of Ohio, have invented certain new and useful Improvements in Printing-Presses, of which the following is a specification.

My invention relates to improvements in printing presses, and, more particularly, to that class or type of job-printing presses in which the platen is stationary and the type bed or form is moved to and from the platen for giving the impressions by means of an oscillating frame.

15 The present invention relates more particularly to automatic feeding-mechanism whereby a single sheet or length of paper is automatically carried and fed through the press in such a manner as to print a number 20 of properly-spaced impressions upon a single blank or sheet of paper.

The primary object of the invention is to produce a generally improved automatic feeding job-printing press which will be exceedingly simple in construction, cheap of 25 manufacture, and efficient in use.

The multi-color mechanism herein shown and described but not claimed, is made the subject matter of a divisional application 30 filed November 3, 1908, Serial No. 462,431.

With these and other ends in view, the invention consists in the novel construction, arrangement, and combination of parts, hereinafter described, illustrated in the accompanying drawings, and particularly pointed out in the appended claims.

Referring to the drawings, forming a part of this specification, Figure 1, is a rear elevation of a press constructed in accordance 40 with my invention. Fig. 2, a front elevation of the same. Fig. 3, side elevation of the same. Fig. 4, detailed plan view of the improved feeding-table showing the reciprocating feeding carrier and the intermittently operated sheet carrier, together with necessary grippers, guides and fingers, the relative location of said grippers, on the gripper-shaft, being slightly modified from that shown in Fig. 1. Fig. 5, a detailed view of 45 the feed mechanism operating-shafts, and connections as they appear from the feeding side of the press. Fig. 6, a detail perspective view of the sheet feeding-carrier gripper-operating tilting-plate.

50 Similar numerals of reference designate

like parts throughout all the figures of the drawings.

The improved press comprises a pair of stationary platen-supporting plates 1, provided with a forwardly-extending base portion 1^a, connected by a rock-shaft 2. The rock-shaft 2, is adapted to rock in the bearing heads 1^b, of the plate 1, and the ends thereof extend out laterally and are connected to the lower ends of the oscillating 55 type-bed carrying frame 3, said frame comprising two arms terminating at their upper ends in bearing heads 4, between which are interposed the stationary axially-rotating ink-distributing rollers and near the front 60 edges 4^a of which is secured the projecting type-bed, all as hereinafter described.

The side plates 1, of the stationary platen-supporting-frame carry a main driving-shaft 5, provided at each end with pinions 6, and 75 at one end with a driving-pulley or fly-wheel A. The driving-shaft 5, may be connected to and driven by any suitable and convenient source of power, and said pinions 6, mesh with a pair of driving-gears 7, on the ends 80 of a second or cam-shaft 8.

The oscillating frame 3, is maintained in proper position and is given the proper oscillating motion relative to the platen by means of a pair of connecting or draw-arms 9, pivoted at one end to the projecting eccentric 85 ends of a rock-shaft 10, and at the other to the gears 7.

The oscillating frame 3, is provided with the usual throw-off mechanism comprising 90 an arm 11, extending from the eccentric shaft 10, and connected to a connecting-bar or link 12, said link being pivotally-connected at its lower end to an oscillating spring-resisted foot-lever 13, extending to the front 95 of the machine and provided with a tread plate 14. The foot-lever 13, is pivotally-secured to one side of the forwardly-extending base portion 1^a by means of a pivot-stud or bolt 15.

The traveling yoke-frame 16, hereinafter described, carrying the traveling inking-rollers, is given the proper reciprocating motion by means of a vertically-movable connecting bar or link 17, the upper end of which is pivotally connected to a lug 18, near the rear or pivoted end of one of the side members 16^a, of the yoke frame. The lower end of the connecting bar or link 17, is pivotally-connected in a bearing-slot at one end of a reciprocating 100 105 110

lever-bar 19, one end of said lever bar being pivotally-secured to the front portion of one of the supporting-plates 1, by means of a pivot bolt 20. The lever bar 19, is provided 5 at one side with an anti-friction roll 21, taking into a cam-slot or way 22, of a gear-wheel 23, mounted on the adjacent supporting-plate 1. The gear-wheel 23, is so geared to the other gears of the press, hereinafter de- 10 scribed, and relative to the gear wheels 7, connected to the draw-arms 9, as to be adapted to move the traveling inking-rollers over the type-form when the latter is moved by the reciprocating frame toward the platen 15 and to remain in contact with the lower inker-roll, beneath the head 4, of the frame, when the type-form makes contact with the platen, and when the type form is moved by the reciprocating frame away from the 20 platen, the traveling inking rollers travel back over the type-form toward the upper inker-roll and remain in contact therewith while the type-form is being carried forward by the oscillating frame 3, for the second impres- 25 sion.

In order to prevent the front edges 4^a, of the type-carrying bearing-heads 4, from coming in contact with the strip or sheet of paper being printed when the type-form is making 30 its impression, the chase and type form 24, are so positioned that their faces project in front of the front edges 4^a, so that the latter cannot engage with the sheet to be printed to mar or otherwise deface the same, and the 35 traveling inking-rollers 25, are provided at their ends with friction-bearing rollers or carrying-wheels or flanges 26, adapted to travel upon and bear against the front edges 4^a, of the bearing heads 4, of the frame. It will be ob- 40 served that the distance between the peripheries of the rollers 25, and the wheels or flanges 26, is substantially equal to the distance, the face of the type-form is projected beyond the front edges 4^a, of the frame, so that the inking-rollers will always be held in uniform 45 inking-contact with the face of the type-form.

The inking-rollers 25, are held in proper position and secured to the side members of 50 the reciprocating yoke-frame 16, by means of a series of longitudinally-movable spring-resisted bearing bars 27, said bars 27, being carried in suitable bearing-openings of the cross-bars or members 28, and provided at 55 their outer ends with hooked bearing-heads 29, taking over pintles 30, at the ends of the inking-rollers. Coil-springs 31, surround the bearing-bars 27, and are interposed between the front cross member 28, and adjustable 60 sleeve-blocks 32, secured to the rear ends of the bearing bars by means of screws 33. By adjusting the sleeve-blocks 32, the resistance offered by the springs 31, may be increased or decreased as desired.

65 The printing-ink is adapted to be received

upon and distributed by a main driving-ink-distributing-roll comprising a series of sections 34, adapted to be adjusted on the shaft 35, whereby the distance between the several sections may be varied as desired. The several sections 34, are adapted to carry different colored inks and to distribute the same in circumferentially-extending sections to the upper and lower inker-rolls 36, and 37, respectively, by means of a pair of intermediate 70 friction-rollers 38, interposed in frictional engagement between the peripheries of the sections of the main ink-distributing roll and the upper and lower inker-rolls 36, and 37. 75

All of the ink-distributing-rolls are given 80 continuous rotation by means of a pulley 39, on the shaft 35, said pulley being driven by a belting 40, (see dotted lines in Fig. 3) passed over idlers 40^a, on the shafts 10 and 2, in the frame 3, and thence over a driving-pulley 41, 85 (see Fig. 1) on the main driving-shaft 5. The side members 16^a, of the reciprocating yoke-member 16, are pivotally-secured at their rear to rearwardly extending bearing lugs 42, by means of pivot-bearings 43, and, 90 it will be understood, that the upper and lower inker-rolls 36, and 37, respectively, continue to rotate while the traveling inking-rollers are in contact therewith in their extreme upper and lower positions, while the 95 impression is being made, thus revolving the traveling inking-rollers and thoroughly distributing the ink thereon.

One of the driving gears 7, meshes with a second gear-wheel 44, (see Fig. 3) said gear-wheel being revolvably-secured to the side of one of the side-plates 1, and provided with a pinion 45, meshing with the cam-gear-wheel 23, hereinbefore referred to.

The shaft 8, is provided with a series of 105 cams 46, 47, 48 and 49, adapted to operate against the ends of a series of spring-resisted crank-arms comprised in the sheet feeding and carrying mechanism, as hereinafter fully described.

One of the side plates 1, of the stationary-supporting-frame, is provided with a pair of laterally-extending supporting-brackets 50, carrying a rock shaft 51, a second rock shaft 52, and a third or cam-shaft 53, said rock-shaft 51, being connected at one end with a crank-arm 54, and at the other end or operator's side of the press, with a longitudinally-slotted arm 55. The rock shaft 52, is provided at one end with an upwardly-extending arm 56, and at the other end or operator's side of the press, with a curved upwardly-extending slotted arm 57, and the cam-shaft 53, is provided with a series of cams 58, 59 and 60, designed to operate 115 against pivotally-mounted oscillating levers, as hereinafter described. The crank arms 61, 62, and 63, are mounted on the rock-shaft 51, and are adapted to oscillate thereon, and 120 all of these crank-arms together with the 125

crank-arm 54, fastened upon the end of the shaft 51, are held against the cams 46, 47, 48, and 49 by means of a series of springs 64.

One end of the crank-arm 62, is pivotally-secured to a curved connecting-arm or link 65, and the upper end of the link 65, is pivotally-secured to an oscillating crank-arm 66, pivotally-mounted on one side of the frame 1, of the press by means of a pivot-bolt 67. 5 One member 66^a, of the oscillating crank arm 66, is adapted to bear upon and oscillate or rock the end of a depending finger-arm 68, extending downwardly from a horizontally-arranged rock-shaft or bar 69, carrying a series of fingers 70, adapted to hold the fed sheet of paper firmly to the feed table 71. The horizontally-arranged shaft or bar 69, is carried at its ends in bearing-brackets 72, (see Fig. 4) secured to or formed integral 10 with the longitudinally-extending guide or way 73, at the lower edge of the feed table 71. The guide or way 73, carries a slidably-mounted reciprocating paper feed-carrier 74, provided at its ends with bearing-brackets 75, carrying the ends of a rock-shaft or bar 76, said shaft or bar being provided with a series of grippers 77, said grippers 77, engaging the lower marginal edge of the fed sheet when the feed-carrier 74, is being 15 moved from left to right or toward the tympan of the press; the grippers 77, being released from the paper when the carrier 74, is moved away from the tympan of the press for taking another feeding-hold upon the sheet of paper being fed, the fingers 70, in the meanwhile securely holding the paper in position for receiving the impressions. However, at the moment the impression is given, both the grippers 77, and the fingers 20 70, engage and hold the sheet firmly in position. The grippers 77, are held in their closed or feeding position by the resistance of the coiled-spring 78, one end being secured to the carrier 74, and the other to a 25 block or head 79, on the shaft or bar 76. One end of the shaft or bar 76, is provided with an arm 80, adapted to take under one edge of a longitudinally-extending oscillating or tilting-plate 81. The plate 81, is provided at its ends, and at one side of the longitudinal center thereof, with pintles 82, mounted in the suitable bearings of the operating frame 1, and is provided with a short laterally-extending arm 83, to which is pivotally-secured a vertically-arranged connecting-arm or link 84, the lower end of said link being pivotally-secured to the oscillating arm 63.

The paper feed-carrier 74, is given the proper reciprocating or longitudinal feeding-movement on the guide or way 73, by means of the upwardly extending arm 56, on the shaft 52, the upper end of said arm 56, being pivotally-secured to a longitudinally-extending connecting-arm 85, one end of which

arm 85, is pivotally-secured to a bearing-lug 86, at the side of the carrier 74. It will also be observed that the longitudinally-extending connecting-arm 85, is provided near each end with horizontal pivot connections 87, so as to permit of various adjustments of the feed table 71, relative thereto, as hereinafter referred to. The paper feed-carrier 74, is given its reciprocating motion by reason of the rocking of the shaft 52, through the medium of the curved upwardly-extending slotted-arm 57, connected to a connecting-arm or link 88, pivotally-secured to one of the arms of the crank-arms 61, which oscillates by reason of its contact with the cam 46. The sheet-feeding-carrier 89, is mounted upon the guide or way 73, at one side of the press, and is provided with grippers 90, carried upon a longitudinal spring-resisted shaft 91, supported at its ends in bearing-brackets 92. The sheet-feeding-carrier 89, is given its proper intermittent reciprocating sheet-carrying and feeding motion by means of a vertically-arranged swinging bar or arm 93, the lower end of which is pivotally-secured 95 to a downwardly-extending lug 94, on one of the supporting-brackets 50, by means of a pivot 95, and the upper or free end of the swinging bar or arm is pivotally-connected to a short connecting-arm or link 96, one 95 of which is secured to a bearing-lug 97, of the sheet-feeding-carrier 89. The connecting-arm or link 96, is also provided with horizontal pivot-connections 98, for the same purpose as pointed out with reference to the 100 connections 87, of the connecting-arm 85. The vertically-arranged swinging-bar or arm 93, is adapted to be moved to its sheet-receiving or initial position, as shown in the drawings, by means of a cam 58, which, 105 (when the swinging-arm or bar 93, has been moved to its extreme travel in carrying the sheet to the press by the means hereinafter described) engagés the laterally-extending anti-friction roller 99. 110

The longitudinally-extending oscillating or tilting-plate 100, similar to the tilting-plate 81, is provided at its ends with pintles 101, taking into laterally-extending bearing-brackets 102, extending from a supporting 115 plate B, of the feed-board supporting-bracket, hereinafter described. One edge of the tilting-plate 100, takes over the end of a crank-arm 103, extending from the shaft 91, carrying the grippers 90, said arm 103, being 120 operated by the tilting-plate 100, against the resistance of a coiled-spring 104, surrounding the shaft 91, thus opening the grippers 90, for the reception of the lower marginal edge of the fed sheet of paper preparatory to being carried by the sheet-feeding carrier 89, to the press. The tilting-plate 100, is provided with a small crank-arm 105, pivotally-connected to a connecting-arm or link 106, the lower end of said link being pivotally- 130

connected to the outer or free end of a horizontally-arranged oscillating lever 107, pivotally-attached at its rear end to the bracket 50, and provided with a depending bearing-portion 107^a, adapted to frictionally-engage with a cam 60, whereby motion is transmitted to the oscillating lever 107, and the tilting-plate 100, connected thereto, as described. A paper guide arm 108, is secured 10 at its base end to a short-shaft 109, having its ends taken into bearing-brackets 110, extending from the lower edge of the feed table and said paper guide arm 108, is adapted to be lowered against the resistance of a coiled 15 spring 111, by means of a short lever 112. The short lever 112, is pivotally-connected to a connecting arm or link 113, the lower end of said link being pivotally-connected to the outer or free end of a horizontally-ar- 20 ranged oscillating lever 114, arranged similar to the lever 107, and provided with a de- pending bearing-portion 114^a, adapted to frictionally engage with a cam 59, whereby motion is given to the paper guide arm 108. 25 Upon referring to Fig. 1, it will be seen that the relation of the parts is such that the depending-portions of the horizontally-ar- ranged levers, 107, and 114, having reached the extreme edges of the cams 60 and 59, the 30 levers are about to drop or be depressed by the resistance of the coiled-springs 104, and 111, thus closing the grippers 90, and elevat- ing the paperguide arm 108, while the hooked draw-arm 115, pivotally-connected to the 35 arm 54, and normally carried by and swing- ing from the connecting-link 116, on the arm 114, is lowered at its free or hooked end 115^a, so as to engage the pin or stud 93^a, of the arm 93, and at the same time the cam-arm 40 45 the lever 54, as it is elevated by the re- sistance of the coiled spring, will cause the engaged arm 115, to draw the upper end of the swinging bar or arm 93, with the at- tached sheet-feeding carrier toward the 50 press. When the sheet-feeding carrier 89, has reached its extreme sheet-delivery pos- 55 60 65 70 75 80 85 90 95 100 105 110 115 120 125 130 135 140 145 150 155 160 165 170 175 180 185 190 195 198 200 205 210 215 220 225 230 235 240 245 250 255 260 265 270 275 280 285 290 295 300 305 310 315 320 325 330 335 340 345 350 355 360 365 370 375 380 385 390 395 398 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 798 800 805 810 815 820 825 830 835 840 845 850 855 860 865 870 875 880 885 890 895 898 900 905 910 915 920 925 930 935 940

neously elevated, and at the moment after the paper-feed carrier 74 has traveled to its extreme sheet-receiving position and its grippers having taken over the lower marginal edges of the sheet, which, as before stated, is now free from the sheet feeding-carrier 89, and its grippers 90. Soon after the paper feeding carrier 74, with its grippers 77, has engaged the sheet the cam 59, will raise the lever 114, thereby elevating the hooked draw-arm 115, through the medium of the connecting link 116, and the cam 58, will engage the anti-friction roller 99, and swing the vertically-arranged arm 93, with the attached sheet-feeding carrier 89, back so to its initial position, as shown in the drawings. In the meantime the paper-feed carrier is carrying the sheet through the press, the number of motions of the paper-feed carrier, or impressions to be given to the sheet to each sheet-carrying delivery-motion of the sheet-feeding carrier 89, being regulated as now described.

One end of the cam-shaft 53, is provided with a ratchet-wheel 122, and the cam shaft 53, with the attached ratchet wheel 122, are given an intermittent motion by means of a pawl-carrying wheel 123, provided with a series of pawls to engage with the ratchet wheel. The pawl-carrying wheel 123, is given an intermittent motion by means of the longitudinally-slotted arm 55, said arm 55, being connected to the pawl-carrying wheel by means of a strap or cord 125, ex- 100 tending about and attached to the periphery of the pawl-carrying wheel 123, and at the other end adjustably secured in the slot of the arm 55, by means of an adjusting-bolt connection 126. The distance through which the cam shaft 53, with its attached ratchet wheel 122, will be carried at each motion or impulse of the slotted arm 55, is regu- 105 lated by moving the adjusting-bolt connec- 110 tion 126, in the slot of the arm 55, and the pawl-carrying wheel 123, being moved against the resistance of a spring 127, at- 115 tached to a strap or cord 128, secured about the periphery of the hub portion 123^a, of the pawl-carrying wheel, and said pawl-carrying wheel will be returned by said spring 127, for 120 the next impulse or motion. The connect- 125 ing-arm or link 88, is pivotally-secured in the slot of the curved forwardly-extending arm 57, by means of an adjusting-bolt connection 129, so that, by moving this adjusting-bolt connection in the slot, the length of the feed- 130 ing-motion or thrust given to the paper-feed carrier 74, may be regulated to correspond with the number of impressions which it is desired to make on each sheet.

The parts of the machine, as shown in the drawings, are adjusted so as to give ten im- 135 pressions to each sheet. The slotted arms 55, and 57, are preferably provided with a graduated scale so as to indicate just where 140

the adjusting bolt connections 126, and 127, should be placed in order to give the number of impressions desired on each sheet.

The platen-supporting frame 1, is provided with a laterally-extending feed-table supporting-bracket 130, and a platen 131, is supported by means of adjustable impression-bolts 132, mounted in the cross members 133, of the platen-supporting frame.

10 One end of the feed table is provided with a large opening adapted to take over the platen 131, and of larger size than the platen so as to form a marginal recess or opening 134, permitting of a movement or adjustment of the feed-table in any direction by means of the adjusting-thumb-nuts 135, in the brackets 136, at the upper edges of the feed-table, thus permitting of an adjusting of the feed-table so that the sheet will be 20 properly positioned and fed to the type-form to be printed. The feed-table is also secured to the outer end of the supporting-bracket by means of a bolt 137, passing through an opening in the bracket of much larger diameter 25 than the bolt, the bolt being secured by means of a thumb nut 138, said thumb-nut bearing against a large washer 139, covering the large opening C, in the bracket through which the bolt passes. The large opening in 30 the bracket will thus permit the bolt, with the attached table, to be shifted about for the adjustment hereinbefore referred to. The horizontal pivot-connections 87 and 98, of the connecting-arms 85 and 96, connected to 35 the paper feed-carrier 74, and sheet feeding carrier 89, respectively, also provide for the adjustments of the feed table just spoken of.

It will be understood that the length of the 40 crank-arms 54, 61, 62, and 63, and the relative sizes of the cams 46, 47 48, and 49, are such that the necessary movements of the parts in their paper feeding and gripping motions relative to each other take place at the right time.

45 It will be observed that the ends of the crank-arms 54 and 61, are curved downwardly forming the downwardly-extending loops 54^a and 61^a, so as to clear the driving shaft 5.

50 When it is desired to print a number of colors at a single impression, as for example, red, blue and black, the sections 34, comprising the ink-distributing roll, are separated from each other and secured upon the 55 shaft 35, as shown in the drawings, and in order to give the ink-distributing roll a lateral motion, whereby to more thoroughly and evenly distribute ink on the contiguous rolls, the shaft 35, is provided at one side with a 60 head 35^a, having a circumferential cam groove or recess 35^b. As the shaft 35, is revolved the requisite to and fro motion of the shaft will be imparted by reason of its engagement with a fixed finger-bracket 35^c, 65 which takes into the cam-groove 35^b.

From the foregoing description, taken in connection with the accompanying drawings, the operation and advantages of my invention will be readily understood.

Having thus described my invention, what I claim and desire to secure by Letters Patent is:

1. In a printing press, a sheet-feeding mechanism, comprising a laterally-extending feed-table provided at its lower edge with a guide, a reciprocating paper-feed carrier mounted on said guide and provided with a plurality of grippers, means for reciprocating said paper-feed carrier, a series of fingers extending above said feed-table, means for moving said fingers from and to said feed-table when said paper-feed carrier is given its to and fro movements, and means for closing and opening said grippers when said feed carrier is given its initial to and fro movements.

2. In a printing-press, a sheet-carrying and feeding mechanism, comprising a laterally-extending feed-table, a guide member on said feed-table, a reciprocating sheet-feeding carrier mounted on said guide, a paper feed-carrier mounted on said guide and carrying a plurality of grippers, means for giving said paper-feed carrier a to and fro motion on said guide, means for closing and opening said grippers when said feed-carrier is given its initial to and fro movements, means for moving said sheet-feeding carrier to said paper-feed carrier when the latter has been given a pre-determined number of to and fro movements, and means for regulating the to and fro movement of said paper-feed carrier on said guide.

3. In a printing-press, a sheet-carrying and feeding mechanism comprising a feed-table provided with a guide at its lower edge, a reciprocating sheet-feeding carrier mounted on said guide and carrying a plurality of grippers, a paper feed-carrier mounted on said guide and carrying a plurality of grippers, pivotally-secured to said paper-feed carrier and provided with an operating-arm, a horizontally-arranged tilting plate mounted on the lower edge of said feed-board and having one edge taking over one end of said operating-arm, means for giving a to and fro motion to said paper-feed carrier, means for releasing the grippers of said sheet-feeding carrier when the sheet carried by said sheet-feeding carrier is engaged by the grippers of said paper-feed carrier, and means for operating said tilting plate.

4. In a printing-press, a sheet-carrying mechanism comprising a laterally-extending feed-table provided at its lower edge with a guide, a paper-guide arm pivotally-secured at the lower edge of said feed-table, a reciprocating sheet-feeding carrier mounted on said guide and provided with a plurality of grippers, a paper-feed carrier mounted on said

guide and carrying a plurality of grippers, means for giving said paper-feed carrier an intermittent to and fro motion on said guide, means for closing and opening said grippers when said paper-feed carrier is given its initial to and fro movements on said guide, means for moving said sheet-feeding carrier to said paper feed-carrier when the latter has been given a pre-determined number of to and fro movements, and means for elevating said paper-guide arm prior to the forward movements of said sheet-feeding carrier.

5. In a printing-press, a sheet-feeding mechanism comprising a feed-table, a longitudinally-extending guide secured thereto, a paper-feed carrier mounted on said guide, a rock-shaft carried by said paper-feed carrier and provided with a plurality of grippers, an operating-arm secured to said rock-shaft, a 10 longitudinally-extending tilting-plate pivotally-secured at the lower edge of said feed table and having one edge taking over the end of said operating-arm, means for giving said paper-feed carrier a to and fro motion on said guide, and means for operating said 15 tilting plate when said paper feed carrier is given its initial rearward motion on said guide.

6. In a printing-press, the combination 20 with a stationary frame carrying a platen, an oscillating frame carrying a type-bed, a laterally-extending feed-table secured to said first named frame and extending from said platen, a guide carried by the lower edge of 25 said feed-table, and a paper feed-carrier mounted on said guide and provided with a plurality of grippers; of means for giving said paper-feed carrier a to and fro motion on said guide when said type-bed is moved 30 to and from said platen, respectively, means for closing and opening said grippers when said feed-carrier is given its initial to and fro movements, a plurality of oscillating fingers extending above said feed table, and means 35 for closing said fingers on said feed-table when the impression is being given and holding the paper in contact with the feed-table when said paper-feed carrier is being given its fro motion.

5. In a printing-press, a sheet-carrying and feeding mechanism, comprising a laterally-extending feed-table, a guide secured thereto, a reciprocating paper-feed carrier mounted on said guide and carrying a plurality of grippers, means for giving said paper-feed carrier a to and fro motion on said guide, means for closing and opening said grippers when said paper-feed carrier is given its initial to and fro movements, a 50 plurality of fingers extending above said feed table, means for moving said fingers from and to said feed-table when said paper feed carrier is given its to and fro movements, a sheet-feeding carrier mounted on said guide and provided with grippers, means

for moving said sheet-feeding carrier to said paper-feed carrier when the latter has been given a pre-determined number of to and fro movements, and means for releasing the grippers of said sheet-feeding carrier when the sheet carried by said sheet-feeding carrier is engaged by the grippers of said paper-feed carrier.

8. In a printing-press, a stationary frame carrying a platen, an oscillating frame carrying a type-bed, a feed-table secured to said stationary frame and extending laterally from said platen, a longitudinally-extending guide secured to the lower edge of said feed-table and provided with a reciprocating paper-feed carrier, a rock-shaft carried by said paper-feed carrier and provided with a plurality of grippers, means for giving said paper-feed carrier a to and fro motion when said type-bed is moved to and from said platen, 75 respectively, means for closing and opening said grippers when said feed-carrier is given its initial to and fro movements, a plurality of fingers extending above said feed-table, and means for moving said fingers from and to said feed-table when said paper feed carrier is given its to and fro movements.

9. In a printing-press, the combination 80 with a stationary frame carrying a platen, an oscillating frame carrying a type-bed, a laterally-extending feed-table secured to said stationary frame, a longitudinally-extending guide at the lower edge of said feed-table, a reciprocating paper-feed carrier mounted on said guide and provided with a plurality of grippers, and means for closing and opening said grippers when said paper-feed carrier is given its initial to and fro movements; of a sheet-feeding carrier mounted on said guide and provided with grippers, a plurality of 85 fingers extending above said feed-table, means for moving said sheet-feeding carrier to said paper-feed carrier when the latter has been given a pre-determined number of to and fro movements, and means for simultaneously elevating said fingers and said grippers of the sheet-feeding carrier after said paper-feed carrier has traveled to its extreme sheet-receiving position and its grippers have engaged the sheet to be fed through 90 the press.

10. In a sheet-carrying and feeding mechanism for printing-presses, the combination 95 with a laterally-extending feed-table provided with a longitudinally-extending guide, a reciprocating paper-feed carrier mounted on said guide and carrying a plurality of grippers, means for giving said paper-feed carrier a to and fro movement on said guide, and means for closing and opening said grippers when said paper-feed carrier is given its initial to and fro movements; of a sheet-feeding carrier mounted on said guide and provided with grippers, means for moving said sheet-feeding carrier to said paper-feed car- 100

rier when the latter has been given a pre-determined number of to and fro movements, and means for releasing the grippers of said sheet-feeding carrier when the sheet carried by said sheet-feeding carrier is engaged by the grippers of said paper-feed carrier.

11. In a sheet-carrying and feeding mechanism for printing-presses, the combination with a reciprocating paper-feed carrier provided with a plurality of grippers, and means for closing and opening said grippers when said paper-feed carrier is given its initial to and fro movements; of a reciprocating sheet-feeding carrier provided with grippers, means for moving said sheet-feeding carrier to said paper-feed carrier when the latter has been given a pre-determined number of to and fro movements, and means for releasing the grippers of said sheet-feeding carrier when the sheet carried by said sheet-feeding carrier is engaged by the grippers of said paper-feed carrier.

12. In a sheet carrying and feeding mechanism for printing-presses, a reciprocating paper-feed carrier, a reciprocating sheet-feeding carrier, means for moving said sheet-feeding carrier to said paper-feed carrier when the latter has been given a pre-determined number of to and fro movements, means for regulating the to and fro movements of said paper-feed carrier, and means for releasing the sheet-feeding carrier when the sheet carried thereby is engaged by said paper-feed carrier.

13. In a sheet-carrying and feeding mechanism for printing-presses, the combination with a reciprocating paper-feed carrier, a plurality of oscillating fingers extending above said paper-feed carrier, an intermit-

tently-reciprocating sheet-feeding carrier, and means for closing said fingers when the impression is being given; of means for releasing the sheet-feeding carrier when the sheet carried thereby is engaged by said paper-feed carrier.

14. In a sheet-carrying and feeding mechanism for printing-presses, the combination with a laterally-extending feed-table provided with a guide, a reciprocating paper-feed carrier mounted thereon, a plurality of oscillating fingers extending above said feed-table, and an intermittently-reciprocating sheet-feeding carrier mounted on said guide; of means for releasing the sheet-feeding carrier when the sheet carried thereby is engaged by said paper-feed carrier, means for moving and holding said fingers in contact with said feed-table when said paper feed-carrier is being given its fro motion, and means for regulating the to and fro movement of said paper-feed carrier on said guide.

15. In a sheet-carrying and feeding mechanism for printing-presses, a reciprocating paper-feed carrier, an intermittently-reciprocating sheet-feeding carrier, a plurality of oscillating fingers, means for closing said fingers when said paper feed-carrier is being given its fro motion, and means for releasing the sheet-feeding carrier when the sheet carried thereby is engaged by said paper-feed carrier.

In testimony whereof I have affixed my signature, in presence of two witnesses:

FRED H. VAN LOOZEN.
